GOLF CLUB GRIP

John J. Baker, Laguna Hills, Calif., assignor to W. J. Voit
Rubber Corporation, a corporation of California

Filed July 13, 1967, Ser. No. 7,795

Term of patent 14 years

(Cl. D34—5)

FIG. 1

FIG. 1 is a front view of a golf club grip showing my new design;

FIG. 2 is a side view of a golf club grip showing my new design; and

FIG. 3 is an end view of the golf club grip.

I claim:

The ornamental design for a golf club grip, as shown.
